UNITED STATES PATENT OFFICE

SAMPSON BROADWIN, OF BROOKLYN, NEW YORK

PATTERN MECHANISM FOR CROCHET KNITTING MACHINES

Application filed October 25, 1930. Serial No. 491,144.

The device, the subject of this invention is intended as a pattern mechanism for crochet knitting machines and has for its special objects the provision of peculiarly formed links 5 and more especially a means for retaining the pattern pins in the links.

It is desirable that the pins which cause a pattern be reliably retained but it is also desirable that means be provided so that the 10 pins may be quickly removed either in the event of wear or when the pattern is to be changed.

I am aware that other constructions have been suggested but the construction that I 15 propose herewith has the particular advantage that the pins are never driven into the link by which they are supported nor are they secured therein in such a way that much time is lost in removing them and another 20 advantage of the invention is that the pins are free to partially rotate during use and therefor the wear will be uniform across the whole head of the pin.

The following is what I consider the best 25 means of carrying out my invention and the accompanying drawings should be referred to for a complete understanding of the specification which follows.

In the drawings:

Fig. 1 is a top plan view of a single link of a pattern chain.

Fig. 2 is a reversed plan view of the link.

Fig. 3 is a side elevation of a pin.

Fig. 4 is a side elevation of a pin taken at 35 right angles to the view in Fig. 3.

Fig. 5 is a much enlarged sectional view of a single socket, and

Fig. 6 is a sectional view of a modified form of pin.

Similar reference numerals indicate like 40 parts in all the figures where they appear.

At 1 I show a chain link and this link is provided with the usual lugs 2, 3, 4 and 5 so that a series of these links may be secured together, the lugs 2 and 3 fitting on the next successive lugs 4 and 5. It is believed however that this construction is well understood and therefore no further description of it is required.

The links 1 are usually formed of alumi-

num or some other metal and each bar or link member is provided with a plurality of lugs as shown at 6 and 7 and any number of these lugs may be provided, but in standard practice each bar is provided with any 55 desirable number of such lugs.

Each lug is centrally drilled to receive the pins as shown at 8 and 9 and in Figs. 1 and 2 a pin is shown in each lug of the bar 1.

Adjacent to and communicating with the 60 perforation through each lug are slots and I have indicated two of these slots at 10 and 11.

Referring to Fig. 2 it will be noted that the bar is recessed under each of the lugs 6-7 and two of these recesses are indicated at 12 and 13, although it will be understood that there is a recess under each lug. The slots or grooves 10 and 11 communicate with the recesses and extending across the bar and through the recess in the lug are spring members such 70 as shown at 14 and 15. These spring members are U-shaped members, the two arms 16 and 17 being connected by a cross bar 18 and I provide pairs of perforations transversely of the bar 1 and extending through the recess 75 for the reception of the spring members. These perforations which should be oval shaped to allow for a free spring operation are shown at 19 and 20 in Fig. 5 and after passing through the perforations the ends of 80 the spring members are clinched inward as shown at 21 and 22.

The pins used with my device are such as are shown in Figs. 3, 4 and 6. These pins are provided with a cross pin 23 which rests 85 on the face of the lug as shown in Fig. 1. The small pin 24 low down or near the end of the pin is intended to pass through the slot 10 and when the pin 8 is revolved through one-half of a complete revolution and in either direction, a spring arm 16 or 17 is forced outward to allow the pin to pass and thereafter the pin 24 rests in the position as shown in Fig. 2.

In Fig. 6 I show a hollow pin which may be employed to lighten the whole device. 95 This pin operates however in the manner above described and the only change is that it may be tubular.

In Fig. 3 I show in dotted lines 25 a washer arranged in the pin 23. The only purpose 100

of this washer is to prevent wear in the event that the links 1 are made of aluminum or soft metal.

As the spring arms 16 and 17 are closely adjacent to the hole through the lug, the pin 8 cannot vibrate loose as it requires a half revolution of this pin to free it or to place it in such a position so that the small pin 24 can be withdrawn through the slot 10.

It will of course be understood that the pins 8 may be of any desired length and that other modifications may be made within the scope of the appended claim without departing from the principle or sacrificing the advantages of the invention.

Having carefully and fully described my invention, what I claim and desire to secure by Letters Patent is:

In a pattern mechanism for crochet knitting machines, a link bar having a plurality of perforated lugs, each said lug being provided with a slot and a recess in said bar under each said lug, a spring member for each said recess and a pattern pin for each said perforation, said pin having a cross pin adapted to rest on the face of a lug and a short pin adapted to pass through the slot in each said perforation and to be engaged by the spring in the adjacent recess.

SAMPSON BROADWIN.
